UNITED STATES PATENT OFFICE.

GEORGE L. HALL, OF NEWARK, NEW JERSEY.

DESIGN FOR A SCREWDRIVER.

59,742.

Specification for Design.

Patented Nov. 22, 1921.

Application filed June 23, 1921. Serial No. 479,931. Term of patent 14 years.

To all whom it may concern:

Be it known that I, GEORGE L. HALL, citizen of the United States, residing at Newark, in the county of Essex and State of New Jersey, have invented a new, original, and ornamental Design for Screwdrivers, of which the following is a specification, reference being had to the accompanying drawing, forming part thereof.

The figure is a plan view of a screwdriver showing my new design.

I claim:

The ornamental design for a screwdriver, as shown.

In testimony whereof I affix my signature.

GEORGE L. HALL.
